(57) **CLAIM**

The ornamental design for a gripping tongs, as shown and described.

DESCRIPTION

FIG. 1 is a front left side isometric view of a gripping tongs in accordance with the new design;

FIG. 2 is a ride side elevational view thereof, the left side elevational view being a mirror image thereof;

FIG. 3 is a top plan view thereof, the bottom plan view being an identical view thereof;

FIG. 4 is a rear elevational view thereof; and,

FIG. 5 is a front elevational view thereof.

The broken lines shown in FIGS. 1 and 4 illustrate portions of the gripping tongs that form no part of the claimed design.

1 Claim, 5 Drawing Sheets
